UNITED STATES PATENT OFFICE.

MELVIN D. COMPTON, OF NEW YORK, N. Y.

PUMP CONTROL.

1,116,998.

Specification of Letters Patent.

Patented Nov. 10, 1914.

Application filed December 13, 1913. Serial No. 806,374.

To all whom it may concern:

Be it known that I, MELVIN D. COMPTON, a citizen of the United States, and a resident of New York, in the county of New York and State of New York, have invented certain new and useful Improvements in Pump Control, of which the following is a specification.

The principal objects of the present invention are to automatically insure the presence in a vessel or container of a supply of air under limited pressure; to provide for automatically connecting and disconnecting a pump or compressor with its driver in response to limited changes of pressure in the air receiver or reservoir, and to provide simple, automatic and reliable means adapted among other things for use in connection with air systems of motor cars or automobiles for automatically maintaining a supply of compressed air under limited pressure by connecting and disconnecting a pump or compressor with some rotating member or element of the car, or automobile.

The invention will be claimed at the end hereof, but will be first described in connection with the embodiment of it chosen for illustration in the accompanying drawings, in which—

Figure 1, is an elevational view, principally in section, of mechanism embodying features of the invention. Fig. 2, is a sectional view on the line 2—2 of Fig. 1, Fig. 3, is a sectional view on the line 3—3 of Fig. 2, and Fig. 4, is a section on the line 4—4 of Fig. 1.

There is an air pump or compressor. It is shown as consisting of a casing 1 having opposed cylinders 2 and 3, each provided with air inlets 4 and with air outlets 5 and appropriate check valves 6 and 7 for the same, and of a pair of pistons 8 connected together through the yoke 9 of an eccentric 10. When the eccentric revolves the pump compresses air and delivers it by way of the offtake 11 to a suitable air tank or receiver, not shown, but from which air is taken as it may be required for any purpose.

12, is a driven shaft and it may be one of the shafts of a motor or automobile. This shaft drives one member 13 of a sliding clutch, the other member 14 of which is connected with the eccentric shaft 15. As shown this is accomplished by intermesh-

ing gears 16 and 17, of which the gear 16 is fast on the shaft 12 and the gear 17 carries the clutch member 13 and is revoluble on a sleeve carried by the frame 18. The clutch member 14 is provided with a projecting sleeve 19, receiving the eccentric shaft 15 and provided with a slot in which a pin 20 on the eccentric shaft is arranged. The spring 21 tends to keep the clutch members in engagement in which position the pump is driven continuously from the shaft 12.

22, is a clutch opening diaphragm and it is arranged to sub-divide a chamber 23.

24, is a plunger, the head of which rests upon the diaphragm and the stem 25 of which engages a shoulder on the clutch member 14. Within the casing 29, there is a check valve 31, which by controlling port 75 30, controls the admission of compressed air from the delivery tube 35 to the diaphragm 22 by way of the opening 33. The check valve is held to its seat by an adjustable spring by means of which the pressure 80 required to open it can be fixed and determined.

28, is a relief valve, connected with a plunger 26, which is acted upon by the air pressure in the tube 35 by means of the bypass 32. This relief valve controls the exhaust of air from the diaphragm by way of opening 36 and exhaust passage 34, although plunger 26 is always in connection with the compressed air, spring 27 beneath 90 it is of sufficient tension to hold the relief valve off its seat until the air pressure has risen to the required predetermined amount.

In the position of the parts shown in the drawings, the clutch members are in engagement and the pump is being driven which means that the pressure of the air supply is less than its limiting pressure, or that air is being used. Under these conditions the 100 check valve 31 is closed and relief valve 28 is open by the pressures of their springs, and the clutch members 13 and 14 are in engagement by the pressure of the spring 21. It will now be assumed that the pressure in 105 the tank or reservoir and, of course, in the off-take 11, rises to its limiting value. This rise of pressure does two things, it closes relief valve 28, shutting off the connection of the diaphragm with the exhaust, and it 110 opens check valve 31, admitting air pressure behind said diaphragm, thereby acting upon

the plunger 24 to throw clutch member 14 out of engagement with clutch member 13. Under these circumstances the pump stops and remains at rest until the pressure in the 5 tank or reservoir and consequently in the pipe 11 and parts connected therewith falls, which it will do, for example, when an additional supply of air is used. When the 10 pressure falls in the port 30 below the point 10 at which it can hold the check valve 31 open, the check valve closes, cutting off the pressure from the diaphragm 22. At the same time the relief valve 28 has opened putting the diaphragm in communication with 15 the exhaust, which allows the plunger 24 to shift and the clutch members to be brought into engagement with each other, starting up the pump. 37 is a diaphragm operative with the plunger 26 and when present it prevents 20 leakage.

It will be obvious to those skilled in the art that modifications may be made in details of construction and arrangement and that changes in the use of the described apparatus 25 can be made without departing from the spirit of the invention, hence it is not intended to limit the invention further than the prior state of the art may require by the use of any particular language that may be 30 used herein.

What I claim is:

1. A pneumatic device comprising the combination of an air compressor and an air line, a driving clutch for the compressor, 35 a diaphragm for throwing the clutch, reversely acting check and relief valves and their ports for admitting and exhausting air to and from the diaphragm, and means for constantly exposing said valves to the air 40 pressure in the line, whereby the compressor is automatically run when the air pressure is below a certain limit and is automatically stopped when the air pressure is above a certain limit.
- 45 2. In a pneumatic device the combination of an air chamber, a diaphragm subdividing the air chamber, reversely acting check and relief valves and their ports for exhausting air to and from the space between one side 50 of the diaphragm and the wall of the chamber, and means for subjecting said valves to differences in air pressure to automati-

cally open and close them, substantially as described.

3. In a pneumatic device the combination 55 of a chamber, a diaphragm subdivided by the chamber, an air line, a spring closed check valve having its head exposed to the line pressure and adapted to admit air to the diaphragm, and a spring opened relief valve 60 having its tail exposed to the air line and adapted to exhaust air from the diaphragm, substantially as described.

4. A pneumatic device comprising the combination of a positively driven shaft, an 65 air line, a compressor, a clutch between the compressor and shaft, a plunger for throwing the clutch, a chamber, a diaphragm subdividing the chamber and coöperating with the plunger, oppositely disposed check and 70 relief valves and their ports for admitting and exhausting air to and from the diaphragm, means for constantly exposing the head of one of said valves and the tail of the other of said valves to the pressure of 75 air in the line, and means for normally closing the check valve and for normally opening the relief valve whereby the compressor is automatically operated from the shaft when the air pressure in the line is 80 low and is automatically disconnected from the shaft when the air pressure in the line is high.

5. A pneumatic device comprising the combination of an air compressor and an air 85 line, a driving clutch for the compressor, a diaphragm for throwing the clutch, reversely acting check and relief valves and their ports for admitting and exhausting air to and from the diaphragm, a second dia- 90 phragm for the relief valve, and means for constantly subjecting said valves to the air pressure in the line, whereby the compressor is automatically run when the air pressure is below a certain limit and is automatically stopped when the air pressure is 95 above a certain limit.

In testimony whereof I have hereunto signed my name in the presence of two witnesses.

MELVIN D. COMPTON.
